UNITED STATES PATENT OFFICE

115,100

DESIGN FOR AN ELECTRIC HEATER

James S. De Masters and John W. Keyes,
Kansas City, Mo.

Application October 3, 1938, Serial No. 80,213

Term of patent 7 years

To all whom it may concern:

Be it known that we, James S. De Masters and John W. Keyes, citizens of the United States and both residing in Kansas City, in the county of Jackson and State of Missouri, have invented a new, original, and ornamental Design for an Electric Heater, of which the following is a specification, reference being had to the accompanying drawing, forming a part thereof.

Figure 1 is a side elevational view of an electric heater showing new design; and,

Fig. 2 is a plan view of the same.

The other side of the electric heater is substantially like the side shown in Fig.1.

We claim:

The ornamental design for an Electric Heater, as shown and described.

JAMES S. DE MASTERS.
JOHN W. KEYES.
